UNITED STATES PATENT OFFICE.

OTTO E. HARRIS, OF INDIANAPOLIS, INDIANA, ASSIGNOR OF ONE-HALF TO ORAN M. PRUITT, OF INDIANAPOLIS, INDIANA.

AIR-LIFT PUMP.

No. 886,053.

Specification of Letters Patent.

Patented April 28, 1908.

Application filed October 14, 1907. Serial No. 397,268.

To all whom it may concern:

Be it known that I, OTTO E. HARRIS, a citizen of the United States, residing at Indianapolis, in the county of Marion and State of Indiana, have invented certain new and useful Improvements in Air-Lift Pumps, of which the following is a specification.

The object of my invention is to produce a simple, efficient center nozzle air lift.

10 The accompanying drawing, which is an axial section, illustrates my invention.

In the drawings, 10 indicates a base casting having a lower opening 11 and perforations or slots 12 in its walls. Formed in the 15 upper end of casting 10 is a spider 13 having a central hub 14 threaded to receive a pipe 15 which, at its lower end, is perforated at 16. Surrounding pipe 15 is a casing or pipe 17 which, at its lower end, is mounted in the up-

20 per end of casting 10 and at its upper end is threaded into a coupling 18. Threaded into the coupling 18 above the upper end of casing 17, is a partition 19 the center of which is threaded to receive the upper end of a bell 20, 25 the lower end of which is outwardly flared to the walls of casing 17 and extended below the upper end of pipe 15 so as to form an annular passage 21, adjustable by means of thread in coupling 18 to regulate or close annular passage 21.

Formed in casing 10 is a passage 22 which, at its lower end, is curved upwardly at the center of casing 10 immediately above opening 11 thereof, and provided with a threaded 35 end adapted to receive a lower threaded end of the nozzle 23 which, at its upper end, is carried above the uppermost perforation 16 and flared outwardly, as shown at 24. The outer end of passage 22 also is threaded to re-

40 ceive the lower threaded end of the air supply pipe 24. Threaded into the upper end of coupling 18 is the water pipe 25 which is extended upwardly to the top of the well. The entire structure, which has been described, is 45 adapted to be projected downwardly into well casing 26, the external dimensions of the casting 10 being a trifle less than the internal diameter of pipe 26.

In operation the structure is submerged in 50 the water of the well to a desired depth, de-

pending upon the desired lift, as is customary, and air under pressure forced downwardly through pipe 24. This air passing upward through nozzle 23 and out through the flared end 24 rushes upward through pipe 55 15 carrying the column of water therein with it and at the same time drawing water upward through openings 11 and 12 into pipe 15, and also drawing water from the lower end of shell 17 through openings 16 into pipe 60 15. As the stream of water and air emerges from the upper end of pipe 15 into bell 20 it draws water upward from shell 17 through the annular passage 21, and the two streams combine in the bell 20 and pass upward 65 through pipe 25. By actual tests I have found the structure herein described to be very highly efficient.

I claim as my invention:

1. An air lift nozzle structure comprising a central air nozzle having an outwardly flared upper end, and a straight water pipe surrounding said nozzle and having induction openings in its lower end below the discharge end of the air nozzle. 70

2. An air lift nozzle structure comprising a central air nozzle having an outwardly flared upper end and a straight water pipe surrounding said nozzle and having induction openings at its lower end below the discharge 75 end of the air nozzle, a shell surrounding said water pipe, the said water pipe having openings in its lower wall forming a communication between its interior and the shell below the discharge end of the air nozzle, and a bell 80 arranged within said outer shell at the upper end of the water pipe and forming an annular suction opening around the upper end of said water pipe. 85

3. An air lift nozzle structure comprising a main shell open at its bottom, a tube arranged in said shell and of smaller diameter than the shell and open at its bottom, a coupling member carried at the upper end of the main shell and adapted to receive the lower 95 end of the water pipe, a bell threaded at its upper end in said coupling member and having a lower end outwardly and downwardly flared and arranged over the upper end of the inner tube, an air nozzle smaller than the in- 100

ner tube and arranged therein in its open lower end and having its upper end outwardly flared, and an air supply tube extending down alongside a main shell to a point near the bottom thereof and thence upwardly into the nozzle.

In witness whereof, I, have hereunto set

my hand and seal at Indianapolis, Indiana, this second day of October, A. D. one thousand nine hundred and seven.

O. E. HARRIS. [L. S.]
